UNITED STATES PATENT OFFICE

LEWIS G. MORRIS TIMPSON, OF PLAINFIELD, NEW JERSEY, ASSIGNOR TO PYRENE-MINIMAX CORPORATION, A CORPORATION OF DELAWARE

FIRE EXTINGUISHING APPARATUS AND METHOD

Application filed July 14, 1928. Serial No. 292,721.

The present invention relates to fire extinguishing apparatus and method and has for an object to provide an improved arrangement for charging a stream of water with fire fighting materials.

The invention has been developed in connection with the production of apparatus for forming fire foam and for convenience such an embodiment of the invention will be more particularly described, but it will be understood that the particular description is illustrative merely and is not intended as defining the limits of the invention.

The nature and objects of the invention will be better understood from a consideration of a particular embodiment thereof for the purpose of which description reference should be had to the accompanying drawing forming a part hereof and in which—

20 Figure 1 is a diagrammatic view of foam forming apparatus embodying the invention, and

Figure 2 is a detail view of the three-way valve 30.

25 When charging a stream with foam forming chemicals by introducing the stream into the top of a container carrying a large charge of powder, the quality of the foam which depends upon the erosion varies considerably as the powder charge is gradually used up. This variation of the quality of the foam is due to the fact that the water is first admitted to the powder container at a point close to the surface of the powder, but, as the 30 charge is gradually exhausted, the water flows through a substantial body of foam before it engages the powder. The present invention provides an arrangement whereby the water is admitted at all times at a point relatively close to the surface of the powder. The point of admission of the water may be changed by manual manipulation or by automatically controlled means as the powder charge is exhausted.

45 The apparatus shown for the purpose of illustrating the principles of the invention comprises a charging tank 5 adapted to contain a considerable charge of material to be loaded into the stream of water carrying the same to the point of use and means for

admitting water thereto first at the top and gradually at points further from the top as the charge of powder is exhausted. As shown, the water is admitted through a number of spray heads 6, 7, 8, 9, the position of each of which is fixed, and means is provided whereby the water is admitted automatically first to the top spray 6 for a predetermined period of time and then successively to the other devices. As the stream of water entering through the sprays is charged with powder, the resultant foam will flow out through the outlet 10 at the top of the tank. In use the tank is fully charged with foam forming powder, for example to the level indicated at 11. The uppermost spray device 6 is suitably positioned with relation to the top of the charge of powder to form effective foam as water is admitted thereto. In the structure illustrated, the uppermost spray device is shown as positioned slightly below the surface of the powder. The other similar spray devices are positioned at spaced distances toward the bottom of the tank.

50 In operation water is first admitted to the uppermost spray head 6 for such period of time as will be necessary to exhaust a certain proportion of the powder whereupon the supply of water to said spray head is gradually closed and water is admitted gradually to the next lower spray head 7. As the powder charge is exhausted the several spray heads are brought into action successively to admit water to the charge at a point relatively adjacent the upper surface thereof.

55 Whether the water is admitted just above or just below the surface of the powder will depend upon the nature of the powder and the character of the loading desired.

60 The admission of water to the several spray heads is preferably automatically controlled. As shown, the flow of water is controlled by valves 12, 13, 14, 15 which, in turn, are controlled by cams 16, 17, 18, 19 on a cam shaft 20 shown in a conventional perspective to indicate the operation thereof. This cam shaft is connected to a suitable timing device. As shown, a float tank 25 is arranged to be gradually filled simultaneously with the flow of the stream being charged. As

the float 26 rises therein, it rocks the cam shaft through the connecting link 27 and arm 28 to open and close the several valves successively. The float tank is connected to the main conduit 29 through a three-way valve 30 and a shut-off valve 31. Valve 30 is so arranged that when weight 36 is on the trigger the water supply to the tank is closed, and the drain from the tank is open, as shown in Fig. 2. This valve is arranged to be opened when the apparatus is set in operation, thus permitting a gradual flow of water to the float tank to gradually fill the same. The shut-off valve 31 may be arranged to be normally open but automatically closed when the float tank is entirely filled.

The three-way valve is shown in closed position but operative to open communication to the float tank. The operating lever 35 may be moved downwardly to open the valve by a weight 36 slideable on the rod 37 secured to the operating lever 35 and supported by a fusible bail 38 connected in an electric circuit 39. When the circuit is closed automatically or manually fusion of the bail 38 will release the weight 36 which, falling, will swing the lever 35 through an angle of 90° to open the valve. The whole apparatus will then be set in operation.

When the cycle of operation is completed the charge of powder in the container 5 will be exhausted and the flow of water to the float tank should be stopped. To this end the valve 31 is arranged to be automatically closed when the water reaches a predetermined level in the float tank. The float 40 provided for this purpose is shown diagrammatically as connected by an arm 41 and a link 42 to the operating lever 43 of the valve 31 to close the same.

The float tank 25 can be emptied through the waste conduit 45 by manual operation of the valve 30.

The foregoing description is illustrative merely and is not intended as defining the limits of the invention.

I claim:

1. In apparatus of the character described for charging a stream with powdered material, the combination with a charging tank of means for passing a stream into said tank at any one of a plurality of predetermined points including means for maintaining the point of inlet in a substantially predetermined relation to the top of a charge of powder in said tank as said powder is carried away from the top by the stream, substantially as described.

2. In apparatus of the character described for charging a stream with powdered material, the combination with a charging tank of means for passing a stream into said tank at any one of a plurality of predetermined points including means for automatically varying the point of inlet of said stream with-

in the tank as the powder is carried away by the stream, the arrangement being such that the inlet point follows the receding surface of the powder, substantially as described.

3. In apparatus of the character described for charging a stream with powdered material, the combination with a tank for storing powdered material having an outlet and a plurality of inlets arranged to follow the receding surface of the powder, of means for automatically controlling the admission of water successively to said inlets, substantially as described.

4. In apparatus of the character described for charging a stream with powdered material, the combination with a tank having an outlet and a plurality of inlets at predetermined points of means for admitting water to said inlets successively for limited periods of time, said means being so constructed and arranged as to maintain a flow into said tank, substantially at the surface of the powder as the level of the surface of the powder lowers, substantially as described.

5. In apparatus of the character described for charging a stream with powdered material, the combination with a tank having an outlet adjacent its top and a plurality of inlets spaced different distances from the top of said tank of means for automatically admitting water successively to said inlets from the uppermost to the lowermost to discharge the water into the tank at substantially the surface of the material as the latter recedes, substantially as described.

6. In apparatus of the character described for charging a stream with powdered material in combination a charging tank adapted to contain a charge of powder, a plurality of inlets for admitting water to said tank at different elevations, a timing device arranged to be automatically set in operation upon operation of the apparatus for admitting water successively to said inlets in a definite sequence so as to follow the recession of the surface of the charge, for predetermined periods of time, substantially as described.

7. In apparatus of the character described for charging a stream with powdered material in combination a charging tank adapted to contain a charge of powder, a plurality of spray devices within said tank at different distances from the top thereof, a plurality of valves controlling the flow of water to said spray devices and means for successively opening and closing said valves successively in a definite sequence to admit water to successive spray devices for limited periods of time so as to follow the receding surface of the charge, comprising a float tank and a cam shaft connected to operate said valves, substantially as described.

8. In apparatus of the character described, a timing device comprising a float tank arranged to be filled gradually, a float therein

and means controlled by the float operating during upward movement thereof for opening, holding open for a predetermined time and then closing a valve, substantially as described.

9. The method of charging a stream with powdered material which comprises maintaining a charge of powder in a tank, flowing a stream of water to and from said charge of powder while periodically changing the point of ingress of said stream to maintain the same at a point relatively near the receding surface of the powder as the powder is exhausted, a predetermined quantity of water being introduced at each point.

10. In apparatus of the character described, a timing device comprising a float tank having an inlet arranged to be filled gradually, a float therein and means controlled by the 15 float operative during upward movement thereof for opening, holding open for a predetermined time and then closing a valve, a second float and means controlled thereby for closing the inlet to the float tank when 20 the liquid therein reaches a predetermined level.

11. The method of charging a stream of water with powdered material for fire extinguishing purposes which comprises introducing the water into a tank containing a charge of the material at successively lower points, maintaining the point of introduction of the water below the receding surface of the charge, and removing the water charged with 35 the material from a point above the point of introduction of the water.

In testimony whereof I have signed my name to this specification this fifth day of July, 1928.

40 LEWIS G. MORRIS TIMPSON.
